DOUBLE-CASING HIGH-PRESSURE PUMP

Edward Hart, San Marino, Calif., assignor to A. O. Smith Corporation, Milwaukee, Wis., a corporation of New York

Application July 31, 1944, Serial No. 547,423

2 Claims. (Cl. 103—108)

1

This invention relates to double casing high pressure pumps of the multi-stage rotary impeller type wherein the pump housing for the impellers is of cast construction embodying passages and volutes giving a high efficiency to the pump, and wherein an outer casing surrounds the pump housing and is adapted to contain fluid under pressure to support the pump housing against tension stresses resulting from the compression of the fluid therein. The fluid in the casing is usually pumped fluid which is under the same pressure as the fluid being discharged from the pump.

Heretofore, the outer casings for such pumps have been of cast or similar construction requiring heavy walls to withstand the high internal fluid pressures. Where corrosion was likely, either the metal of the casing throughout its thickness had to be of an expensive corrosion resistant alloy, or else an added weight of some alloy sheet liner had to be inserted therein and properly sealed against leakage of fluid behind the same. Such pumps were expensive and heavy in weight, detracting from their commercial applications.

The object of the present invention is to greatly reduce the cost of such pumps and to lighten the weight of the same so that they may be employed more readily in competition with other types of pumps.

According to the invention the outer casing is composed of a number of relatively thin layers of metal superimposed and welded along one or more longitudinal seams and welded to end flange members or closures for supporting the pump therein. Where corrosion is encountered, the inner layer is constructed of suitable corrosion resistant alloy while the remainder may be of less costly steel, all of the layers being utilized for the retention of the pressure fluid.

Expensive casting operations for the casing are eliminated, and due to the higher quality of rolled stock of relatively thin plates, the total wall thickness and weight of the casing is considerably reduced. The layers are fabricated in tight contact to effect uniform stress distribution therein, while the flexibility of the several layers provides a structure more free from fabrication stresses and more reliable in the confining of the pressure fluid.

The accompanying drawings illustrate an embodiment of the invention.

In the drawings:

Figure 1 is a side elevation with parts broken 55 many subsequent layers may be applied as may be

2 away and sectioned showing the right hand end of the pump; and

Fig. 2 is a similar section through the left hand end of the pump.

5 The pump comprises a cast pump housing 1 having a rotary shaft 2 extending longitudinally axially thereof. The left hand end of housing 1 is bolted to the cover plate 3 and the right hand end has a slip joint sealed by the annular ring 5 and centering the housing in a separator piece 10 forming the inner wall of a suction chamber in the end housing 4. End housings 6 are bolted to cover plate 3 and housing 4, respectively, and contain bearings for the ends of the pump shaft 2. The shaft extends through the end of one of the housings 6 to be driven by any suitable means.

10 The housing 1 contains the impellers 7 secured on the shaft 2 in volute chambers 8 in the housing. As many impellers 7 may be employed 15 as desired within the limits of proper shaft alignment and support, the pump illustrated having ten impellers and being a ten-stage pump.

15 The inlet for the pump is provided in end housing 4 where the lateral intake 9 supplies fluid 20 to a throated circumferential chamber 10 leading to the first stage impeller 11. From impeller 11 the fluid is directed through passages in housing 1 to successive stages until it is finally discharged through the central port 12 in the side 25 of the pump housing.

20 In construction, the end housing 4 has a circular flange 13 thereon for welding to the end of the outer cylindrical casing 14 by the arc deposit 15. The cover plate 3 is bolted to an end 30 flange member 16 welded to the opposite end of the casing 14 by the arc deposit 17. Welds 15 and 17 serve to secure the members longitudinally and the bolted end plate 3 and flange 16 provide for assembly of the pump.

35 In accordance with the invention, the casing 14 is constructed of a plurality of layers of rolled plate formed into superimposed cylindrical layers to provide a multi-layer construction in which each layer is in uniform pressure engagement 40 with its adjacent layer or layers.

40 In constructing the casing, the first layer 18 is first formed by rolling or pressing a flat plate to cylindrical shape and the longitudinal seam is welded, as by an arc deposit 19. Subsequent layers 20 are similarly formed and then applied either successively or at one time and tightened upon the inner layer by tension bands and then welded along the longitudinal seams 21. As 45 many subsequent layers may be applied as may be

necessary to provide a cylinder capable of withstanding the fluid pressures involved, having regard to the thickness of the layers and the strength of the metal. The drawings show four layers 20.

In practice the layers should range between one-eighth and one-half inch in thickness in order that they be assured of proper quality of steel. The relatively thin plates are readily formed and applied without danger of internal stresses from fabrication, and the shop equipment for constructing the casing from such layers is simple and inexpensive. Furthermore, the relatively thin layers provide a structure which is highly flexible to stresses and which effects a ready and uniform distribution of the working stresses throughout the same.

The inner layer 18 may be of non-corrosive alloy of a composition known to be resistant to attack from the fluid being pumped, and is welded into the structure in a manner adapting it to take its share of stress under working loads, along with the other layers.

The casing 14 has a central discharge outlet 22 disposed in alignment with the outlet port 12 of the pump housing 1. The space or chamber 23 between housing 1 and casing 14 serves to retain pumped fluid under pressure from said outlet 12 and to thereby surround the pump housing 1 during operation with fluid under pressure.

By reason of the protection of housing 1 by the external fluid pressure the housing can be thinner and much lighter in weight, thereby making the casting of it less expensive and its handling during machining and fabrication of the pump less difficult.

The outer casing withstands both the longitudinal and circumferential pressure of the fluid, thereby relieving the pump housing of all tension stress during operation of the pump.

The invention may have various embodiments within the scope of the accompanying claims.

I claim:

1. In a double casing high pressure pump of the class described, an outer cylindrical casing constructed of a plurality of superimposed layers of rolled metal plate welded in close pressure engagement with one another for withstanding high internal fluid pressures, a lateral intake head

welded to said casing at one end and a flange welded to the casing at the other end, an end head secured to said flange, aligned bearings carried by said heads for a pump shaft, a pump enclosed in said casing and having a rotary shaft extending therethrough and mounted in said end bearings, a plurality of impellers mounted on said shaft and operative in series to provide a high pressure discharge for the pumped fluid, said pump being supported at its ends only by said end heads and being continuously and radially spaced from said outer casing to provide a closed chamber therebetween for substantially the full length of the pump, and a lateral discharge outlet welded to said casing substantially centrally thereof in alignment with the discharge port of the pump and connecting with the space between said pump and casing to dispose fluid in said space under circumferential and longitudinal pressure protecting the pump against internal fluid pressures during operation of the pump.

2. In a double casing high pressure pump of the class described, an outer cylindrical casing constructed of a plurality of superimposed layers of rolled metal plate welded in close pressure engagement with one another for withstanding high internal fluid pressures, an end head providing an inlet to said pump for fluid to be pumped welded to the end of the casing and another end head removably secured to the casing, a pump enclosed in said casing and having a rotary shaft extending therethrough and mounted in said end heads, a plurality of impellers mounted on said shaft and operative in series to provide a high pressure discharge for the pumped fluid, said pump being supported only by said end heads and being continuously and radially spaced from said outer casing throughout substantially the full length of the pump, and means comprising a discharge outlet disposed substantially centrally of the casing and connecting with the space between said pump and casing to provide fluid between the pump and casing under a circumferential and longitudinal pressure equal to the pressure of the fluid at said discharge to protect the pump against internal fluid pressures during operation of the pump.

EDWARD HART.
